UNITED STATES PATENT OFFICE.

JAMES SLOCUM, OF DETROIT, MICHIGAN.

SPARK-ARRESTING DEVICE.

Application filed May 21, 1925. Serial No. 31,793.

My invention aims to provide a simple, durable and inexpensive spark arresting device that may be easily and quickly mounted on top of a chimney, stack or other smoke and spark outlet member to arrest sparks, hot cinders and other inflammable matter that might set fire to the roofs of buildings and to structures near by. It is a well known fact that considerable property is destroyed annually because of sparks and burning embers emitted by chimneys, and this is particularly true in connection with any furnace or heating apparatus having a forced draft which caused large sparks to be emitted and if there is a wind the sparks are carried a considerable distance. It is also true in connection with wood and coal burning stoves, and furnaces, especially those on farms, and many dwellings, barns and outbuildings have been destroyed because of sparks passing through stovepipes and chimneys.

There is constantly forming in stovepipes and chimneys a creosote substance which clings to the inside walls, which formation is caused by heat and gases and the various temperatures at different times, and the formation continues until some time when there is a very hot fire or something is burned in the stove or furnace which creates a large blaze, which sets fire to the coating or scale on the inside of the stovepipe or chimney. The burning of the creosote formation creates a great heat in the chimney and a draft which causes particles of the formation or scales to be emitted from the chimneys to the roof and other buildings, and such red hot scales or burning fire brands burn for some time and frequently destroy buildings.

My invention further aims to provide a spark arrester wherein a foraminous body and a series of screens or baffle members are adapted to prevent the escape of sparks or inflammable matter, without retarding a draft in the chimney, the device being so constructed that should one or all of the baffle screens become clogged, the draft may pass around and between said baffle screens through openings of sufficient size to care for the draft, and still arrest any and all sparks. Each spark arresting device includes novel means for clamping it in place and each spark arresting device is constructed to withstand the elements of nature and

not detract from the general appearance of a chimney.

My spark arresting device will be herein-after specifically described and then claimed, and reference will now be had to the drawing, wherein

Figure 1 is a vertical sectional view of the device mounted on a chimney, and

Fig. 2 is a vertical longitudinal view of the same.

The spark arresting device is constructed of strong woven wire mesh material, made rust-proof, to form a foraminous body having side walls 5, end walls 1, and somewhat of a dome shaped or convex top wall 2.

Secured to the end walls 1 by rivets 3 or other fastening means are the flanges 4 of side walls 5 and said side walls are formed with inturned curved baffle members 6 cooperating with the top wall 2 in providing side openings 7.

Connected to the end walls 1 by rivets 8 or other fastening means are the flanges 9 of a central inverted V shaped baffle member 10 which has its longitudinal edges underlying the inner edges of the end baffle members 6, thus providing a tortuous or sinuous passage through the device so that any sparks or inflammable matter will be arrested before exhausting from the side openings 7.

Connecting the side walls 5, adjacent the lower edges thereof, is a tie rod 11 and mounted on said tie rod are a plurality of spacing members 12. These spacing members of various lengths are employed for correctly positioning resilient bowed clamping members 13 which have coiled portions about the tie rod 11 and the bowed ends 14 of said clamping members are adapted to engage each corner of the inner walls 15 of the chimney 16 on which the device is mounted. The clamping members 13 may be made of resilient non-rusting steel not affected by heat or cold and the resilient or spring ends 14 may be proportioned so as to engage the inner surface of the bricks or other building material from which the chimney is made. With the clamping members 13 spaced apart there may be a four-point engagement with the chimney preferably in each corner to firmly anchor the device on top of the chimney. The ends of each clamping member may be connected by a string or other inflammable member to

temporarily hold the ends in a retracted position while the device is being placed in position on the chimney, and then by setting fire to the string the ends of the clamping members will be released to forcibly engage the walls 15 of the chimney. The release of the clamping members is automatic and it is obvious that said clamping members will fit in various kinds and sizes 10 of chimney openings, and it is an easy matter to make the foraminous body and its foraminous baffle members or screens of such size as may be required for various kinds of chimneys.

15 It is now apparent that any sparks being emitted by the chimney will encounter the central baffle or screen 7 and should wind deflect the sparks towards the side walls 5, the sparks will be either arrested by said 20 side walls or the baffles or screens 6 thereof. Should sparks escape these baffles or screens they will encounter the top wall 2 and the possibility of sparks completely escaping is so remote that the spark arresting device 25 may be considered a perfect safety factor by the users. The foraminous body and its baffle members avoid any interference with a draft in the chimney as ample by-path space has been allowed and should soot and 30 other matter accumulate on the device, the soot can be burned or cleaned off from time to time.

It is thought that the utility of my invention will be apparent without further 35 description, and while in the drawing there

is illustrated a preferred embodiment of my invention, it is to be understood that the structural elements are susceptible to such variations and modifications as fall within the scope of the appended claims. 40

What I claim is:

1. A spark arresting device adapted to be held relative to the upper end of a chimney, said device comprising a foraminous body, foraminous side baffle members in said body, and a foraminous center baffle member in said body, cooperating with said side baffle members in providing a tortuous passage for sparks through said device, said central baffle member being inverted V- 50 shaped with its edges extending under said baffle members.

2. A spark arrester for a chimney, comprising a foraminous body affording a free uninterrupted chimney draft and a tortuous 55 spark passage, and resilient means adapted to be held in a retracted condition when positioning said arrester on a chimney and automatically released for engagement with the inner chimney walls to hold said arrester in position on said chimney. 60

3. A spark arrester comprising a foraminous body having end walls, a series of baffle members in said body, a tie rod connecting the side walls of said body, and resilient clamping members carried by said tie rod. 65

In testimony whereof I affix my signature.

JAMES SLOCUM.
